UNITED STATES PATENT OFFICE.

WILLIAM H. STEWART, OF KANSAS CITY, KANSAS, ASSIGNOR OF ONE-FOURTH TO BENJAMIN H. BARR, OF KANSAS CITY, MISSOURI.

BALING-PRESS.

No. 930,998.

Specification of Letters Patent.

Patented Aug. 10, 1909.

Application filed August 12, 1905. Serial No. 274,006.

To all whom it may concern:

Be it known that I, WILLIAM H. STEWART, a citizen of the United States, residing at Kansas City, in the county of Wyandotte 5 and State of Kansas, have invented certain new and useful Improvements in Baling-Presses, of which the following is a specification.

My invention relates to improvements in 10 baling-presses; and one of my objects is to provide gearing for imparting positive forward and backward strokes to the plunger so that recourse need not be had to springs, or the expansive force of the material under 15 compression, for retracting the plunger. By avoiding the necessity of forcing the material several inches beyond the retainers of the press in order to gain its expansive force time will be saved, and by dispensing with 20 springs the power now required in overcoming their tension and also in obtaining excessive compression of the material will be conserved for the purpose of compressing said material to the normal density of a bale, and 25 the shock to which the press is subjected by the rebound of the plunger when suddenly retracted by springs and the expanding material, will be avoided.

Another object is to arrange the power 30 mechanism as closely as possible to the plunger in order to avoid undue strain and friction on the working parts of the press.

A further object is to arrange the reach 35 and the plunger-stem in such manner that they will be close to the ground when the press occupies an operative position, so the draft animals can easily step over said reach and stem while compressing the material.

Heretofore, so far as I am aware, in all 40 baling-presses operated by horse-power, the reach and the plunger-stem have been arranged so far above the ground as to render it impossible for the horses, while passing over said reach and plunger, to exert sufficient 45 force to give final compression to a charge of material, hence it has been impracticable to obtain more than three strokes of the plunger to the revolution of the sweep to which the team is hitched.

50 In order that the invention may be readily understood reference will now be made to the accompanying drawings, in which:—

Figure 1 represents a broken side elevation 55 of a baling-press provided with my improvements. Fig. 2 is a broken plan view of same

with the baling-case in section, taken on line II—II of Fig. 1. Fig. 3 is an enlarged broken plan view of the power-end of the press. Fig. 4 is a central vertical section of same taken on line IV—IV of Fig. 3. Fig. 5 is a section of the fifth-wheel of the press, taken on line V—V of Fig. 4. Fig. 6 is a front elevation of a casting employed in securing the power mechanism to the front axle of the press. Fig. 7 is a cross-section of the power 60 mechanism taken on line VII—VII of Fig. 3.

In said drawings, 1 and 2 designate the front and rear axles of the press which are mounted upon carrying-wheels 3 and 4, respectively.

5 designates a baling-case mounted upon the rear axle and provided with the customary hopper 6 and retainers 7.

8 designates a casting provided with a split-sleeve 9 and a pair of diverging arms 10 which latter are bolted at their rear terminals to the sides of the baling-case.

11 designates a tubular reach secured at its rear end in sleeve 9 by means of a machine-screw 12 and a bolt 13 which latter 75 draws the split-sleeve tightly around the rear end of the reach.

14 designates a stationary spur-gear arranged in a horizontal plane and provided at its rear side with a split-sleeve 15 which is 80 drawn tightly around the tubular reach by a bolt 16. The forward portion of the spur-gear is carried by the upper diverging arms 17 of a casting consisting of said arms, a sleeve 18 through which the forward portion 85 of the tubular reach extends, and a fifth-wheel member 19 which rests upon a circular fifth-wheel member 20 provided with segmental flanges 21 overlapping the ends of member 19. Member 20 has a reinforcement 90 22 at its underside secured upon axle 1 by means of U-bolts 23. Gear 14 is rightangular in cross-section, as shown in Figs. 4 and 7, and has internal teeth 24 integral at their lower ends with an annular shoulder 25 arranged in the same horizontal plane with another annular shoulder 26 integral with the inner edge of a horizontally arranged annular web 27 forming the lower portion of gear 14.

105 28 designates a driven spur-gear concentrically arranged within gear 14 and provided with external teeth 29 the lower ends of which rest upon shoulder 26 and thus support said driven gear. The smooth portion 110

30 of the periphery of the driven gear is journaled in shoulder 26 to receive the thrust hereinafter described, and thus relieve teeth 29 and a pair of intermediate pinions 31 of said thrust. Gear 28 is reinforced at its lower portion by an integral annular flange 32 and provided with a boss 33 for a purpose hereinafter described. Pinions 31 mesh with teeth 24 29 and are arranged to travel 10 in an annular space 34 between said teeth, they being carried by stub-shafts 35 depending from bosses 36 formed integral with an annular cover 37 which overlaps teeth 24 29 and thus excludes dust and dirt from space 15 34. Said cover is journaled in the upper smooth portion 14^a of gear 14 and is held in position by clips 38 secured to the upper portion of gear 14 by machine-screws 39. Cover 37 is rotated by means of a sweep 40 20 secured thereto by machine-screws 41 and abutting against the flat sides of bosses 36 to relieve said machine-screws of the shearing strain to which they would otherwise be subjected. 25 42 designates a pitman pivotally secured at its forward end upon a shouldered screw 43, engaging boss 33, and at its rear end to a pin 44 extending through the rear terminal of a plunger-stem 45 and a sleeve 46 secured 30 thereto. The plunger consists of said stem 45, which extends through the reach, and a head-block 47 which latter is reciprocably arranged in the baling-case and secured to the forward end of the stem. 35 When the sweep is rotated a sun-and-planet motion is imparted to gear 28 and the pinions 31 which latter rotate upon their own axis and also travel around the common axis of gears 14 and 28. The rotation 40 of gear 28 will cause the pitman to move back and forth and thus reciprocate the plunger so the latter will successively compress each charge of hay or other material as it is fed into the baling-case from the hopper. The 45 plunger will advance with decreasing speed and increasing power until the pitman reaches the position shown in Figs. 2 and 3, and as both the forward and backward strokes are obtained by the positive gearing 50 above described, springs and the expansive force of the compressed charges will not be required to retract the plunger, hence the latter need only move forward a slight distance beyond the retainers to insure the latter engaging the material when the plunger moves backwardly. Consequently the time 55 and labor usually required in forcing the material several inches beyond the retainers, in order to obtain the expansive force of each 60 charge upon the plunger, and in overcoming the tension of the springs will be saved.

The thrust produced by the pitman pulling forwardly upon the plunger will be transmitted to shoulder 26 and the abutting face 65 of gear 28, and as these abutting surfaces

are arranged but a slight distance above the plunger-stem the strain produced when applying power a considerable distance out of line with the point of use will be avoided, it of course being understood that the closer 70 the power is applied to the major axis of the plunger, the less strain there will be on said plunger and the gearing.

As the greater portion of the plunger-stem is housed in the tubular reach said stem may 75 be made comparatively light, because the reach will prevent it from buckling under the compressive force exerted thereon during the operation of baling. Another advantage derived in thus arranging said stem resides 80 in the fact that when the machine is placed upon the ground, as shown by dotted line *a* in Fig. 1, the draft animals will have no difficulty in stepping over the reach even when compressing a charge, consequently the gear- 85 may be arranged to impart three or more forward strokes to the plunger to each revolution of the sweep, as the speed of said plunger need only be governed by the rapidity at which material can be conveniently fed into 90 the baling-case.

Although I have shown the preferred construction of my baling-press, I of course reserve the right to make such changes as properly fall within the spirit and scope of 95 the appended claims.

Having thus described my invention, what I claim and desire to secure by Letters-Patent, is:—

1. In a baling-press, two gears one of 100 which is journaled in the other, a pinion meshing with said gears and arranged to travel around their common axis, and means for operating said pinion.

2. In a baling-press, a stationary gear, a 105 driven gear journaled therein, a pinion meshing with said gears, means for operating said pinion, a baling-case, a plunger reciprocably arranged therein, and suitable means for connecting the plunger to one of the gears. 110

3. In a baling-press, two gears one of which is journaled in the other, a pinion meshing with said gears, means for operating said pinion, a baling-case, a plunger reciprocably arranged therein, and a pitman pivotally secured to the journaled gear and the 115 plunger.

4. In a baling-press, in combination, two gears, one of which is journaled in the other, pinions meshing therewith, a sweep for turning said pinions around the common axis of the gears, a baling-case, a plunger reciprocably arranged therein, and suitable means for connecting the plunger to one of the 120 gears.

5. In a baling-press, gears concentrically arranged, pinions meshing therewith, a cover journaled in one of the gears and adapted to carry the pinions around the common axis of said gears, means for rotat- 125 130

ing said cover, a baling-case, a plunger reciprocably arranged therein, and suitable means for connecting the plunger to one of the gears.

5 6. In a baling-press, two concentrically arranged gears, an annular shoulder on one of said gears in which the other gear is journaled, a pinion meshing with said gears, means for operating said pinion, a baling 10 case, a plunger reciprocably arranged therein, and suitable means for connecting the plunger to one of the gears.

7. In a baling-press, two concentrically arranged gears, an annular shoulder on one 15 of said gears, a smooth portion on the periphery of the other gear embraced by said annular shoulder, a pinion meshing with said gears, means for operating said pinion, a baling-case, a plunger reciprocably ar- 20 ranged therein, and suitable means for connecting the plunger to one of said gears.

8. In a baling-press, a stationary gear which is rectangular in cross-section, the 25 lower portion of said gear consisting of a horizontally arranged annular web, another gear

journaled in said web and having teeth overlapping the same, a pinion meshing with said gears, means for operating said pinion, a baling-case, a plunger reciprocably arranged therein and extending beneath the gears, and suitable means for connecting the plunger to the journaled gear. 30

9. In a baling-press, a baling-case, a plunger reciprocably arranged therein, a reach secured at one end to the baling-case and 35 suitably supported at its opposite end, a stationary gear, a sleeve formed integral with said gear and embracing the reach, another gear journaled in the stationary gear, pinions meshing with the gears and arranged to 40 travel in an annular space between said gears, means for operating said pinions, and means for connecting the plunger to the journaled gear.

In testimony whereof I affix my signature, 45 in the presence of two witnesses.

WILLIAM H. STEWART.
